UNITED STATES PATENT OFFICE.

EDGAR L. FULLER, OF EVERETT, MASSACHUSETTS.

HAMMOCK.

1,106,554.

Specification of Letters Patent. Patented Aug. 11, 1914.

Application filed May 16, 1911. Serial No. 627,506.

To all whom it may concern:

Be it known that I, EDGAR L. FULLER, a citizen of the United States, residing in Everett, county of Middlesex, and State of Massachusetts, have invented an Improvement in Hammocks, of which the following description, in connection with the accompanying drawings, is a specification, like letters on the drawings representing like parts.

This invention relates to a hammock of that class in which a rigid mattress supporting frame is suspended from an overhead support.

The present invention has for its object to provide hammocks of the class described with head and foot pieces which are capable of being moved from a substantially vertical position into various angular positions, whereby the full length of the hammock is available, when the occupant desires to lie down full length, and whereby either end piece may be inclined and used as a support for the back and head of the occupant, when the latter desires to assume a sitting position.

These and other features of this invention will be pointed out in the claims at the end of this specification.

Figure 1 is a side elevation of one form of hammock embodying this invention. Fig. 2, an end elevation of the hammock shown in Fig. 1. Fig. 3, a detail in plan on an enlarged scale of a portion of the mattress supporting frame, and Figs. 4 and 5, details to be referred to.

In the present instance, I have shown one known construction of hammock which comprises a mattress supporting frame composed of side rails, rods or bars *a* and end bars or rods *b*, preferably metal pipes which are suitably connected together to form an open frame within which is located a bottom composed of links *c* connected together and yieldingly secured to the side and end bars or rods *a*, *b* by springs *d*, and upon which the mattress *e* is supported.

The mattress supporting frame is suspended from an overhead support of any suitable construction and not herein shown, and in the present instance said frame is suspended by link chains 10 secured at their lower ends to the side bars or rods *a* near the opposite ends of the same.

The hammock as thus far described may be of any usual or well-known construction,

and the present invention has for its object to provide the same at one end and preferably at both ends, with an end piece or frame, which is adjustable into different angular positions to form a support for the back of the person using the hammock.

In the present instance I have shown a back support at each end of the hammock, and as both are alike a detailed description of one will suffice to enable the invention to be understood.

The back supporting piece herein shown comprises a frame preferably of metal and provided with extensible side bars or arms, 70 and in the present instance the upper member of each side arm is made as a hollow pipe or tube 15, open at its lower end and pivotally secured at its upper end to one of the side chains 10 by a pin or rivet 16. The 75 upper member 15 of the side arms on opposite sides of the hammock are shown as connected by a cross piece 17 of piping, which is integral with the upper member 15. Each side arm is provided with a lower member, 80 preferably made as herein shown and comprising a rod 18, which has its upper end inserted into the upper member 15, and has its lower end pivotally secured by a pin or rivet 20 to the free ends of a strap 21, which is bent 85 substantially at its middle to form an eye 22 of greater diameter than the side rod *a* of the mattress supporting frame, so that the said eye can be moved longitudinally thereon. The eye 22 may be practically closed by a 90 block 23 of metal, which is interposed between the arms 21 of the strap and is secured thereto by the rivet 24. The space between the upper members of the side arms may be closed by a piece 25 of canvas, duck 95 or like material, and a pillow 26 may be detachably secured to the link chains and rest on the canvas piece 25.

In operation, the back supporting frames are normally in a substantially vertical upright position as shown at the right in Fig. 1, and when in this position, the hammock may be utilized for its full length.

When the occupant of the hammock desires to recline in the hammock with the 105 head elevated, the eyes 22 of the lower members of the back supporting frame are slid along the side bars or rods *a*, until the said frame has been moved into the desired angular position as represented at the left in 110 Fig. 1. As the eyes 22 are slid along the side rails or rods *a*, the rods 18 are partially

withdrawn from the hollow members 15 of the side arms, and said hollow members are turned on their pivots 16.

The eyes 22 may be secured in their adjusted position on the side rails by mechanical means if desired, or they may be frictionally secured by the weight of the occupant of the hammock bending or springing the side bars or rails a sufficiently to cause them to engage upper and lower edges of the eyes 22, after the manner represented in Fig. 1. In either case the back-supporting frame is securely held in its adjusted position.

I have herein shown one construction of adjustable supporting frame for the hammock, but it is not desired to limit the invention to the particular construction shown. The mattress *e* may be of any usual construction, such as now commonly employed in hammocks of the character described.

Claims.

1. The combination with a hammock provided with a mattress-supporting frame having side rails, and flexible means connected at their lower ends with the mattress-supporting frame to suspend the same, of a movable back-supporting frame having its upper end interposed between said flexible means and pivotally connected thereto at its opposite sides and having extensible side arms in sliding engagement with the side rails of said mattress supporting frame, substantially as described.
2. The combination with a hammock provided with a mattress supporting frame having side rails, and means to suspend the same, of a movable back supporting frame

comprising tubular side arms pivotally connected at their upper ends with said suspending means, rods extended into said tubular arms, and straps pivotally connected with said rods and provided with eyes through which the side rails of the mattress supporting frame extend, substantially as described.

3. The combination with a hammock provided with a mattress-supporting frame having side rails, and link chains connected at their lower ends with the said frame near the ends thereof, of a movable back-supporting frame interposed between the said link chains and having tubular side arms pivoted near their upper ends to said link chains and having extensible lower arms movable in said tubular arms and in sliding engagement with the side rails of said mattress-supporting frame, substantially as described.

4. The combination with a hammock provided with a mattress-supporting frame having side rails, and flexible means connected at their lower ends with the mattress-supporting frame to suspend the same, of a movable back-supporting frame having its upper end pivotally connected at its opposite sides to said flexible means and having extensible side arms in sliding engagement with the side rails of said mattress-supporting frame.

In testimony whereof, I have signed my name to this specification in the presence of two subscribing witnesses.

EDGAR L. FULLER.
